US0D1040850S

(12) **United States Design Patent** (10) Patent No.: **US D1,040,850 S**
(45) Date of Patent: ** Sep. 3, 2024

(54) **DISPLAY SCREEN HAVING A GRAPHICAL USER INTERFACE**

(71) Applicant: **Altria Client Services LLC**, Richmond, VA (US)

(72) Inventors: **Terry Bache**, Richmond, VA (US); **Ryan McGinley**, St Neots (GB); **Nicola Westgarth-Flynn**, St Neots (GB); **Eric Hawes**, Midlothian, VA (US); **Raymond W. Lau**, Glen Allen, VA (US); **Zack W. Blackmon**, Richmond, VA (US)

(73) Assignee: **Altria Client Services LLC**, Richmond, VA (US)

(**) Term: **15 Years**

(21) Appl. No.: **29/848,258**

(22) Filed: **Aug. 1, 2022**

(51) LOC (14) Cl. **14-04**

(52) U.S. Cl.

USPC **D14/489**

(58) **Field of Classification Search**

USPC **D14/485-495**
